(57) **CLAIM**

The ornamental design for a drone, as shown and described.

DESCRIPTION

FIG. 1 is a front, top, left-side perspective view of the drone in an open and assembled state.

FIG. 2 is a front view thereof.

FIG. 3 is a rear view thereof.

FIG. 4 is a left view thereof.

FIG. 5 is a right view thereof.

FIG. 6 is a top view thereof.

FIG. 7 is a bottom view thereof.

FIG. 8 is a front, top, left-side perspective view of the drone in a closed and assembled state.

FIG. 9 is a front view thereof.

FIG. 10 is a rear view thereof.

FIG. 11 is a left view thereof.

FIG. 12 is a right view thereof.

FIG. 13 is a top view thereof.

FIG. 14 is a bottom view thereof.

FIG. 15 is a front, top, left-side perspective view of the drone in a folded and disassembled state.

FIG. 16 is a front view thereof.

FIG. 17 is a rear view thereof.

FIG. 18 is a left view thereof.

FIG. 19 is a right view thereof.

FIG. 20 is a top view thereof; and,

FIG. 21 is a bottom view thereof.

1 Claim, 15 Drawing Sheets
